GOLF BALL RETRIEVER ATTACHMENT

John D. Strickland, 828 Fay Drive, Trevose, Pa.

Filed May 21, 1963, Ser. No. 74,980

Term of patent 14 years

(Cl. D34—5)

I claim:

The ornamental design for a golf ball retriever attachment, substantially as shown.
